[57] CLAIM

The ornamental design for an evaporator panel to be wrapped around a solar and other atmospheric energy sources hot water heater, as shown and described.

DESCRIPTION

FIG. 1 is a front perspective view of an evaporator panel to be wrapped around a solar and other atmospheric energy sources hot water heater, showing my new design in flattened condition;

FIG. 2 is a front elevation view thereof, the rear being a mirror image of that shown;

FIG. 3 is a left side elevation view thereof;

FIG. 4 is a right side elevation view thereof;

FIG. 5 is an enlarged top plan view thereof;

FIG. 6 is an enlarged fragmentary front elevation view of the top portion thereof; and

FIG. 7 is an enlarged top plan view of an evaporator panel to be wrapped around a solar and other atmospheric energy sources hot water heater, bent into a curved form.

FIG. 3.

FIG. 2.

FIG. 4.
